APPARATUS FOR ELECTROLYSIS OF FUSED
ELECTROLYTES

Robert J. McNitt, Perth Amboy, N. J.

Application February 24, 1939, Serial No. 258,161

7 Claims. (Cl. 204—247)

This invention relates to the electrolysis of a fused electrolyte and more particularly to a new method and apparatus for carrying out such electrolysis.

The invention will be fully understood from the following description read in conjunction with the drawing which is a central vertical section through one particular embodiment of the apparatus of my invention and one form of apparatus in which the method of my invention may be carried out, namely a cell for the production of light metals.

Referring to the drawing, cell 1 comprises the outer shell 2 which may, for example, be formed of iron. Shell 2 is lined with refractory material 3. Anode 4 is of graphite and is vertically and centrally positioned within shell 2. In the form illustrated the anode is of cylindrical form. Cathode 5 is an annulus supported by radial arms 6 extending through shell 2. Anode and cathode are electrically insulated from shell 2, and are connected respectively to a source of positive and negative electricity of a voltage and amperage suited to the electrolysis to be conducted, in accordance with usual practice. The space immediately surrounding the anode is bounded by cylindrical perforated diaphragm 7 surmounted and supported by dome 8 communicating with exit pipe 9. Dome 8 is in turn supported by beams not shown which rest on top of shell 2. Since the anodic products are generated and collected in the space bounded by diaphragm 7 and the walls of dome 8, these define the anode compartment. Conversely, since the cathodic products are generated and collected in that part of the cell containing the cathode which is bounded laterally by diaphragm 7 and the inner surface of refractory material 3 and bounded above by the hood shaped partition, that part of the cell is defined as the cathode compartment. The section of the cell directly above the cathode compartment has the primary function of facilitating the removal of the light metal. Materials for replenishing the electrolyte may be introduced into this section in fluid or solid state.

In the specific example of the practice of my invention herein described, the electrolyte is a fused bath of sodium chloride which may contain other salts, favorably influencing the temperature or efficiency of electrolysis of the sodium chloride. In this case the products of electrolysis consist of chlorine and metallic sodium. The chlorine is generated and collected in the anode compartment and conducted from the cell

through pipe 9. The metallic sodium is liberated in liquid phase and is of lesser specific gravity than the electrolyte and therefore rises in duct 20 and flows over the cell wall in duct 21. But, in accordance with the usual practice under the prior art, it may be collected and removed from the cell in any other suitable manner.

I have found that the electrolyte from the cathode compartment circulates to the upper surface of the bath and becomes more or less contaminated with the formation of secondary products.

My invention is particularly concerned with the suppression of this effect, and I shall now describe the particular form and function of the partition or separator between the cathode compartment and the section surmounting the cathode compartment and the manner in which I utilize this partition or separator to obtain this end.

As shown in the drawing, this partition or separator comprises member 10 consisting of flange 11 carried by dome 8, terminating in depending annular flange 12. The partition or separator also includes member 13 comprising the flange 14 secured in refractory lining 3 and terminating in upstanding annular flange 15, forming an annular trough adjacent the cell wall. As is evident from this construction, the partition or separator 20 separates section 16 surmounting the cathode compartment from the cathode compartment and this section and the cathode compartment overlap vertically for a distance while the members 10 and 13 define annular duct 18 extending from the 30 upper part of the cathode compartment downwardly into the lower part of the section 16 surmounting the cathode compartment.

The trough shown in the drawing is not restricted to a position adjacent the cell wall, as 40 I may weld to member 13 an upright member substantially parallel with flange 15, forming the outer surface of the trough so that the trough may be placed in any desired position.

It will, of course, be understood that duct 18 45 need not be annular in form and may, in fact, be a pipe extending from the upper part of the cathode compartment, downwardly into the depression, forming the lower part of the section surmounting the cathode compartment. It will 50 similarly be obvious that this depression need not take the form of an annular trough, but may be merely a cup surrounding the outlet of the duct.

Preferably, the liquid in the trough or other 55 depression surrounding the outlet of the duct is

heavier than the electrolyte adjacent thereto in the upper part of the cathode compartment. I may maintain this condition without the use of any other liquid than the electrolyte by keeping the electrolyte in said trough or other depression cooler than the electrolyte in the upper part of the cathode compartment. In the form shown in the drawing this is automatically accomplished by the fact that the trough is positioned adjacent the cell wall so that some cooling at this point takes place. If, however, the trough or other depression is not so positioned, the electrolyte therein may be kept cooler and therefore heavier than the electrolyte adjacent thereto in the upper part of the cathode compartment by any suitable means for removing heat from the bath in the trough or other depression, such as chilled surfaces therein, or in the bath adjacent thereto.

Alternatively I may, of course, introduce into the trough or other depression a liquid immiscible with the electrolyte and heavier than the electrolyte, as, for example, molten lead, or I may introduce into the trough or other depression granular materials insoluble in the electrolyte and heavier than the electrolyte. The result is in either case a complete or substantially complete sealing off of section 16 from the cathode compartment, which seal may be effectively made after dome 8 and the attached member 10 have been positioned or simultaneously therewith. The partition and seal hereinabove described may be incorporated in an electrolytic cell for the purpose of preventing or suppressing circulation of electrolyte from the cathode compartment to the surface of the bath even though no hood shaped trough is required for the collection of light metal. In case a complete sealing off is obtained, the electrolyte which is decomposed in the cathode compartment may be replaced with bath taken from section 16 above by means of a small tube 19. In accordance with my method and apparatus, it will be seen that the fluid pressure of the electrolyte necessary to cause the metal to rise in pipe 20 is fully and automatically maintained, due to the free communication between section 16 and the cathode compartment notwithstanding the suppression of those currents which would otherwise carry electrolyte from the cathode compartment to the surface of the electrolyte.

The foregoing specific description of one embodiment of my invention is for purposes of illustration and not of limitation. It will, of course, be understood that the invention herein described is susceptible of embodiment in other forms of electrolytic cell than the specific form herein described, and for this reason the invention is to be limited only by the appended claims wherein I have endeavored to claim broadly all inherent novelty.

I claim:

1. In an electrolytic cell adapted to produce light metal by electrolysis of a fused electrolyte, a centrally disposed anode compartment, including means for separately collecting gas generated in said anode compartment, a cathode external to said anode compartment, a partition between said cathode and the upper surface of the electrolyte external to said anode compartment, said partition consisting of an upper and lower part, said upper part consisting of a first horizontal annulus and a vertically disposed annular flange carried by and depending from said first horizontal annulus, the lower part of said partition consisting of a second horizontal annulus positioned

below said first horizontal annulus and a vertically disposed annular flange carried by and extending upwardly from said second horizontal annulus, said depending and upstanding flanges being spaced apart and defining a duct originating in the space below said partition and terminating in the space occupied by fluid electrolyte above said partition, said duct extending downwardly adjacent the point at which it terminates in the space above said partition.

2. A cell according to claim 1 including in addition means for maintaining the electrolyte adjacent the point at which said duct terminates in said space above said partition at a lower temperature and a higher specific gravity than the electrolyte adjacent the point at which said duct originates in the space below said partition.

3. In an electrolytic cell adapted to produce by electrolysis of a fused electrolyte metal in liquid phase of lesser specific gravity than the electrolyte, a vessel having a bottom and a side wall and within said vessel a centrally disposed anode compartment including means for separately collecting gas generated in said anode compartment, a cathode compartment separate from and external to said anode compartment, means for separately collecting liquid metal generated in and rising from said cathode compartment, a partition between said cathode compartment, and the upper surface of the electrolyte external to said anode compartment, said partition consisting of an upper and lower part, said upper part consisting of a first horizontal annulus and a vertically disposed annular flange carried by and depending from said first horizontal annulus, the lower part of said partition consisting of a second horizontal annulus positioned below said first horizontal annulus and a second vertically disposed annular flange carried by and extending upwardly from said second horizontal annulus, said depending and upstanding flanges being spaced apart and defining a duct originating in the space below said partition and terminating in the space occupied by fluid electrolyte above said partition, said duct extending downwardly adjacent the point at which it terminates in said space, the point at which said duct terminates in said space being located adjacent the side wall of said vessel whereby the electrolyte adjacent the point at which said duct terminates in said space is maintained at a lower temperature and a higher specific gravity than the electrolyte adjacent the point at which said duct originates in the space below said partition.

4. In an electrolytic cell adapted to produce light metal by electrolysis of a fused electrolyte, a vessel having a bottom and a side wall and within said vessel a centrally disposed anode compartment, a submerged anode within said compartment, a gas collecting hood surmounting said anode compartment and extending upwardly through the upper surface of the bath, a cathode compartment external to and surrounding said anode compartment, a submerged cathode within said cathode compartment, a feed compartment surmounting said cathode compartment external to and surrounding said anode compartment, and a partition between said cathode compartment and said feed compartment adapted to prevent upward movement of electrolyte from said cathode compartment into said feed compartment.

5. In an electrolytic cell adapted to produce light metal by electrolysis of a fused electrolyte, a vessel having a bottom and a side wall and within said vessel a centrally disposed anode com-

partment, a submerged anode within said compartment, a gas collecting hood surmounting said anode compartment and extending upwardly through the upper surface of the bath, a cathode compartment external to and surrounding said anode compartment, a submerged cathode within said cathode compartment, a feed compartment surmounting said cathode compartment external to and surrounding said anode compartment, a partition between said cathode compartment and said feed compartment, and a liquid seal in said partition whereby fluid electrolyte may move from said feed compartment into said cathode compartment through said seal while flow of electrolyte from said cathode compartment into said feed compartment is suppressed.

6. In an electrolytic cell adapted to produce light metal by electrolysis of a fused electrolyte, a vessel having a bottom and a side wall and within said vessel a centrally disposed anode compartment, a submerged anode within said compartment, a gas collecting hood surmounting said anode compartment and extending upwardly through the upper surface of the bath, a

cathode compartment external to said anode compartment, a submerged cathode within said cathode compartment, a feed compartment surmounting said cathode compartment, a partition between said cathode compartment and said feed compartment, and a duct originating in said cathode compartment and extending therefrom through said partition into said feed compartment, said duct extending downwardly adjacent the point at which it terminates in said feed compartment, whereby fluid electrolyte may move from said feed compartment into said cathode compartment through said duct while flow of electrolyte from said cathode compartment to said feed compartment is suppressed.

7. A cell according to claim 6 including in addition means for maintaining the electrolyte adjacent the point at which said duct terminates in said feed compartment at a lower temperature and higher specific gravity than the electrolyte adjacent the point at which said duct originates in said cathode compartment.

ROBERT J. McNITT.
